EARTH TAMPER OR THE LIKE

Thomas Murphy, Mount Healthy, Ohio

Application February 5, 1941, Serial No. 377,538

10 Claims. (Cl. 94—49)

This invention relates to improvements in an earth tamper or similar tool for compacting various substances such as earth, concrete, cinders, and the like.

An object of the invention is to provide a tamper made in sections that may be attached or detached, as desired, to alter the tamping area and the weight of the tool so as to suit the tool to various kinds or types of work.

Another object of the invention is to provide a tool of the character stated, including readily accessible and serviceable means for effecting quick attachment and detachment of the sections for the purposes mentioned above.

A further object is to provide a sectional tool of the kind referred to, which is so designed that it may be cast from metal without the use of complicated and expensive patterns, thereby to minimize the cost of manufacture.

Another object is to provide the tool sections with cooperative means including correspondingly tapered walls such that use of the tool tends always to preclude accidental separation of the sections during usage.

A further object is to provide a tamper having detachable sections of concentric ring formation, which may readily be hung upon a nail or other hanger for immediate accessibility when not in use.

The foregoing and other objects are attained by the means described herein and illustrated in the accompanying drawing, in which:

Fig. 1 is a vertical section of one form of tamper embodying the invention.

Fig. 2 is a perspective view of a modified form of tamper.

Fig. 3 is a perspective view of the central plug section of the tamper in either of its forms.

Fig. 4 is a perspective view of an intermediate ring section of the Fig. 2 tamper.

Fig. 5 is a perspective view of the outer ring section of the Fig. 2 tamper.

Fig. 6 is a cross-sectional view taken on line 6—6 of Fig. 4.

The two forms of tool illustrated by the drawing are primarily the same, the only substantial difference being that the Fig. 1 form is rendered lighter in weight by casting grooves or depressions in the outer faces of the sections, as indicated at 6 and 7. The plug or central section 8 likewise may be lightened, if desired. In the Fig. 2 form of the device, metal may be omitted in the same manner, or if preferred, the sections may be cored out to render them hollow. It should be understood that both the Fig. 1 and the

Fig. 2 forms include appropriate means, for example the bayonet slot connections shown, for locking the sections together. These do not show on Fig. 1, because it is a cross-sectional view.

Referring first to Figs. 2 to 6 of the drawing, the characters 8, 9 and 10 indicate respectively, the central plug section, the intermediate ring section, and the outer ring section, of the improved tamper. The central plug section comprises an inverted truncated cone portion 12 and a shank 13, bored or otherwise formed with an elongated passageway of the character indicated at 14 of Fig. 1. The bore or passageway is adapted to receive a long wooden handle, which may be secured in position by means of a pin or rivet passing transversely therethrough at 15.

The conical portion 12 is tapered downwardly and inwardly, to provide a tamping area 16 at the lower end of the plug section, the tamping area being plane or solid so as to perform the service of compacting earth or other loose material to be tamped. The outline of the tamping area 16 is of full circle extent.

Along the tapered portion 12 there is formed an upright channel 17 extending from the meeting line 18 between the shank and the cone portion, downwardly to substantially the periphery of the tamping area 16. The upper end of the channel terminates in the material of the shank, as shown, and is there widened so as to provide a step 19 and abutment 20, the latter being in substantial parallelism with the side 21 of the channel. In order that the channel may not end within the confines of the circular tamping area 16, the lower end of the channel is curved outwardly as at 22 to provide an edge 23 coinciding with the outer limit of the circle that defines the tamping area. If desired, the curve 22 may be quite long and may extend to the top of the channel, so that the channel wall 21 would be substantially triangular.

The lower conical portion 12 of the central plug section 8 is adapted to fit snugly within the corresponding tapered central opening 24 of the intermediate ring section 9, the tapered surfaces being so related that when the portion 12 of the plug section is fully inserted, the tamping area 25 of the ring section will be coplanar with the tamping area 16 of the plug section. An integral lug 26 projecting inwardly of the tapered opening 24, is adapted for reception within the channel 17 of the plug section when the parts are assembled, and upon reaching the upper end of the channel the lug 26 may be positioned upon the

step 19 against the abutment 20, by simply imparting a partial rotation to the ring section 9, in counterclockwise direction. The engagement of the resultant bayonet slot structure precludes the possibility of accidental separation of the parts during use of the tamper. When the parts 8 and 9 are assembled as stated, with the lug 26 resting upon the step 19, a suitable wedge or a stick of wood or the like may be inserted into the channel 17 so as to block possible rotation of the one part relative to the other.

The upper portion 27 of the intermediate ring section 9 slopes downwardly and outwardly to a line 28, where it meets a truncated cone shaped wall 29 which is adapted to fit within a correspondingly tapered opening 30 of the outer ring section 10, just as the part 12 of the plug section fits the tapered opening 24 of the intermediate ring section. A channel 31 corresponding to the channel 17 of the plug section 8 is formed in the tapered wall 29, and terminates in an edge 32 that coincides with the outer peripheral edge that defines the tamping area 25. At its upper end, the channel 31 terminates in the top portion 27 of the intermediate ring section, and is there widened to form the step 33 and an abutment 34 at right angles to the step. As will be understood by reference to Figs. 4 and 5, the tapered wall 29 is insertable into the corresponding tapered opening 30 of the outer ring section 10 provided that the integral lug 35 be aligned with the channel 31. Upon so assembling the parts 9 and 10, the lower face of lug 35 will assume a position level with the step 33 while the tamping area 25 rests within the plane of the tamping area 36 of the outer ring section 10. With the parts of the bayonet slot connection thus related, it is necessary only to rotate the outer ring section relative to the intermediate ring section 9 for disposing the lug 35 over the step 33 and against the stop 34 for locking the parts in assembled position.

After the parts have been locked as stated, the upper end of channel 31 will be exposed and if necessary, a wedge of wood or other material may be inserted or driven downwardly toward the edge 32 of the channel for the purpose of precluding rotation of the ring sections to the unlocking or disengaging position. Upon removal of the wedge, the bayonet slot elements may be disengaged to effect separation of the ring sections. In the event that the parts become tightly joined at the tapered openings, by reason of the entry of foreign material, or the like, they may readily be disassociated by applying a sharp blow to one of the upstanding abutments 37 carried by the upper face of the outer ring section 10. A similar abutment 38 may be provided on the intermediate ring section to receive a sharp blow, if necessary, in effecting disassociation of the intermediate ring section from the plug section of Fig. 3. The abutments 37 and 38 may be furnished in any suitable manner, such as by casting them integrally with the metal of the sections.

When the device is completely assembled in accordance with the Fig. 2 illustration, the several tamping areas 16, 25 and 36 rest in a common plane, thereby to gain the effect of a solid tamping, or stomping tool. The tool resulting from assembling all of the sections as shown, is useful for tamping large areas, but when smaller areas are to be tamped or when the tamping force is to be confined to a limited area, one or both of the ring sections may be disconnected

from the central plug section 8, leaving the limited tamping arc 16 available for service. It will be noted that by reason of the fact that the lower ends of channels 17 and 31 are closed, foreign matter being tamped will not readily enter the channels and obstruct them.

With reference to Fig. 1, it should be understood that the bayonet slot construction is incorporated therein, and that the parts fit together in exactly the same manner specified in the description of Figs. 2 to 6. In order to reduce the weight of the assembly, the intermediate section 90 of Fig. 1, and the outer ring section 100, may be grooved or cut away as indicated at 6 and 7. Should it be considered desirable to furnish an abutment corresponding to the abutments 37 and 38 of Figs. 5 and 4, ribs or webs 39 and 40 may be furnished upon the parts 90 and 100, to receive the blows of a hammer or other available tool.

In each form of the invention, the bottom 41 of the handle bore or socket 14 will have thereon an upstanding wedge 42 adapted to split the lower end of handle 43 when the handle is driven into the bore or socket. A portion of the bore or socket at its lower end preferably is flared outwardly as at 43, so as to increase its diameter where the split will occur in the lower end of the handle, thereby rendering the connection secure and incapable of becoming loose. The pin or rivet 15 is to be driven through a transverse aperture in the handle subsequently to driving the lower end of the handle to its ultimate position with respect to the upstanding wedge 42. The wedge may be cast integrally with the plug 8, or it may be a separate part inserted into the handle bore, as desired. Fig. 1 clearly indicates the manner in which the tamping areas of the several tool sections cooperate to form a planar surface for the lower end of the tool. The figure indicates also the manner in which the concentric rings fit to one another and to the tapered lower end of the plug section, in the fully assembled condition of the tool.

Should it be deemed necessary or desirable to furnish a tool of the Fig. 2 construction, with the weight reduced, the parts may be lightened in the manner suggested by Fig. 1, or alternatively, by utilizing cores in the molding of the various parts, to render them hollow. It should be understood that the device of Fig. 3 will include the type of bore and a wedge therein, the same as is illustrated by Fig. 1. The bayonet slot connection is to be considered illustrative only, of a number of possible modes of locking the parts together, and various other modifications and changes may be made in the structural details of the device, within the scope of the appended claims, without departing from the spirit of the invention.

What is claimed is:

1. In a tool of the class described, the combination of a central earth tamping plug including an upright handle and having a bottom tamping area exposed always substantially at right angles to the handle, a detachable tamping section having a bottom tamping area for application to the plug with the tamping areas in a common plane, to selectively increase the effective tamping area of the tool and separable cooperative mounting means on the plug and said tamping section for temporary mounting of the tamping section upon the plug.
2. In a tool of the class described, the combination of a central earth tamping plug includ-

ing an upright handle and having a tamping area exposed substantially at right angles to the handle, a detachable tamping ring having a substantially central opening and a surrounding planar tamping area, and separable means for temporarily mounting the tamping ring about the central plug with the tamping area of the ring in coplanar relationship with the tamping area of the plug.

3. In a tool of the class described, the combination of a central earth tamping plug including an upright handle and having a tamping area substantially at right angles to the handle, a detachable tamping ring having a substantially central opening and a surrounding planar tamping area, and separable means for temporarily mounting the tamping ring about the central plug with the tamping area of the ring in coplanar relationship with the tamping area of the plug, the plug and the opening of the ring being correspondingly tapered and fitted to limit entry of the plug into the opening upon establishing the stated coplanar relationship of the tamping areas.

4. In a tool of the class described, the combination of a central tamping plug having a lower tamping area, a detachable tamping ring having a substantially central opening and a surrounding planar tamping area, the plug and the opening of the ring being correspondingly tapered and fitted to limit entry of the plug into the opening to the extent of establishing a coplanar relationship of the tamping areas, and separable means for temporarily mounting the tamping ring about the central plug with their tamping areas disposed in a common plane.

5. In a tool of the class described, the combination of a central tamping plug comprising a shank and an inverted truncated cone shaped end whose tapered wall defines a full circular bottom tamping area of the plug, said tapered wall being channeled from the tamping area upwardly toward the shank and stepped with an offset portion providing a bayonet slot open where the shank meets the tapered wall, a tamping ring having a lower tamping area with a central opening therein, said opening being tapered in correspondency with the taper of the plug, and dimensioned to limit insertion of the plug into the opening to the extent of establishing a coplanar relationship of the tamping area of the plug to the tamping area of the ring, and a lug in the opening adapted for reception in the channel of the plug wall, to lock the parts together upon partially rotating the ring to effect engagement of the lug with the step of the channel.

6. In a tool of the class described, the combination of a central tamping plug comprising a shank and an inverted truncated cone shaped end whose tapered wall defines a full circular bottom tamping area of the plug, said tapered wall being channeled from the tamping area upwardly toward the shank and stepped with an offset portion providing a bayonet slot open where the shank meets the tapered wall, a tamping ring having a lower tamping area with a central opening therein, said opening being tapered in correspondency with the taper of the plug, and dimensioned to limit insertion of the plug into the opening to the extent of establishing a coplanar relationship of the tamping area of the plug to the tamping area of the ring, and a lug in the opening adapted for reception in the channel of the plug wall, to lock the parts

together upon partially rotating the ring to effect engagement of the lug with the step of the channel, leaving the channel open at the shank and closed at the tamping areas for retaining a wedge inserted therein.

7. In a tool of the class described, the combination of a central tamping plug comprising a shank and an inverted truncated cone shaped end whose tapered wall defines a full circular bottom tamping area of the plug, said tapered wall being channeled from the tamping area upwardly toward the shank and stepped with an offset portion providing a bayonet slot open where the shank meets the tapered wall, a tamping ring having a lower tamping area with a central opening therein, said opening being tapered in correspondency with the taper of the plug, and dimensioned to limit insertion of the plug into the opening to the extent of establishing a coplanar relationship of the tamping area of the plug to the tamping area of the ring, and a lug in the opening adapted for reception in the channel of the plug wall, to lock the parts together upon partially rotating the ring to effect engagement of the lug with the step of the channel.

10 8. In a tool of the class described, the combination of a central tamping plug having a handle-receiving bore and a lower tamping area substantially at right angles to the axis of the bore, an upstanding wedge in the bore having its wedging angle directed away from the tamping area and toward the open upper end of the bore, the bore in the region of the wedge being enlarged to accommodate the split and spread the end of a handle driven into the bore and over 15 9. In a tool of the class described, the combination of a central tamping plug having a handle-receiving bore and a lower tamping area substantially at right angles to the axis of the bore, an upstanding wedge in the bore having its wedging angle directed away from the tamping area and toward the open upper end of the bore, the bore in the region of the wedge being enlarged to accommodate the split and spread the end of a handle driven into the bore and over 20 10. As a new article of manufacture, a tool head having a handle bore open at one end and a bottom closing the opposite end of the bore, the bore being enlarged near the closed end thereof, and a wedge upstanding upon the bottom of the bore with its wedging faces directed toward the open end of the bore, to split a wood handle driven into the bore and to spread the split portion of the handle into the enlargement of the bore.

25 10. In a tool of the class described, the combination of a central tamping plug having a handle-receiving bore and a lower tamping area substantially at right angles to the axis of the bore, an upstanding wedge in the bore having its wedging angle directed away from the tamping area and toward the open upper end of the bore, the bore in the region of the wedge being enlarged to accommodate the split and spread the end of a handle driven into the bore and over 30 11. In a tool of the class described, the combination of a central tamping plug having a handle-receiving bore and a lower tamping area substantially at right angles to the axis of the bore, an upstanding wedge in the bore having its wedging angle directed away from the tamping area and toward the open upper end of the bore, the bore in the region of the wedge being enlarged to accommodate the split and spread the end of a handle driven into the bore and over 35 12. In a tool of the class described, the combination of a central tamping plug having a handle-receiving bore and a lower tamping area substantially at right angles to the axis of the bore, an upstanding wedge in the bore having its wedging angle directed away from the tamping area and toward the open upper end of the bore, the bore in the region of the wedge being enlarged to accommodate the split and spread the end of a handle driven into the bore and over 40 13. In a tool of the class described, the combination of a central tamping plug having a handle-receiving bore and a lower tamping area substantially at right angles to the axis of the bore, an upstanding wedge in the bore having its wedging angle directed away from the tamping area and toward the open upper end of the bore, the bore in the region of the wedge being enlarged to accommodate the split and spread the end of a handle driven into the bore and over 45 14. In a tool of the class described, the combination of a central tamping plug having a handle-receiving bore and a lower tamping area substantially at right angles to the axis of the bore, an upstanding wedge in the bore having its wedging angle directed away from the tamping area and toward the open upper end of the bore, the bore in the region of the wedge being enlarged to accommodate the split and spread the end of a handle driven into the bore and over 50 15. In a tool of the class described, the combination of a central tamping plug having a handle-receiving bore and a lower tamping area substantially at right angles to the axis of the bore, an upstanding wedge in the bore having its wedging angle directed away from the tamping area and toward the open upper end of the bore, the bore in the region of the wedge being enlarged to accommodate the split and spread the end of a handle driven into the bore and over 55 16. In a tool of the class described, the combination of a central tamping plug having a handle-receiving bore and a lower tamping area substantially at right angles to the axis of the bore, an upstanding wedge in the bore having its wedging angle directed away from the tamping area and toward the open upper end of the bore, the bore in the region of the wedge being enlarged to accommodate the split and spread the end of a handle driven into the bore and over 60 17. In a tool of the class described, the combination of a central tamping plug having a handle-receiving bore and a lower tamping area substantially at right angles to the axis of the bore, an upstanding wedge in the bore having its wedging angle directed away from the tamping area and toward the open upper end of the bore, the bore in the region of the wedge being enlarged to accommodate the split and spread the end of a handle driven into the bore and over 65 18. In a tool of the class described, the combination of a central tamping plug having a handle-receiving bore and a lower tamping area substantially at right angles to the axis of the bore, an upstanding wedge in the bore having its wedging angle directed away from the tamping area and toward the open upper end of the bore, the bore in the region of the wedge being enlarged to accommodate the split and spread the end of a handle driven into the bore and over 70 19. In a tool of the class described, the combination of a central tamping plug having a handle-receiving bore and a lower tamping area substantially at right angles to the axis of the bore, an upstanding wedge in the bore having its wedging angle directed away from the tamping area and toward the open upper end of the bore, the bore in the region of the wedge being enlarged to accommodate the split and spread the end of a handle driven into the bore and over 75
